ELECTRIC TOASTER

John R. Gomersall, Elgin, Ill., assignor to McGraw
Electric Company, Elgin, Ill., a corporation of
Delaware

Application February 23, 1950, Serial No. 145,753

12 Claims. (Cl. 219—19)

1

The present invention relates to electric heaters and particularly to heating elements having resistance conductors enclosed in glass tubes or the like.

For use in toasters and the like glass-enclosed heaters have certain advantages, including the protection of the resistance conductor against oxidation and mechanical injury, and the provision of good support for the conductor while permitting free radiation of heat therefrom. But glass becomes less and less insulating as its temperature increases, and although with proper construction the temperature of the glass tube can be kept well below that of the heating conductor itself, it is desirable in certain devices to provide further insulation in the supports for the tube. Furthermore, because of the brittleness of glass it is important that the glass tube be so supported that it will not be subjected to severe strains or shocks.

Objects of the invention include the provision of an improved, glass-enclosed electric heating element for a toaster, the provision of a new and improved support for such a heating element, and the provision of an improved electric toaster construction. To this end I have provided an improved construction wherein the heating element is mounted at its two electric terminals and given support at additional points only by an improved low-leakage mounting, and wherein the tube is self-supporting and so convoluted that its own resilience provides protection against mechanical shocks. These and other objects and advantages will be apparent from the following description of one specific embodiment which illustrates the manner in which the invention may be carried out. In the drawings:

Figure 1 is a pictorial view of a toaster partly broken away to show a heating element construction therein which constitutes the preferred form of the present invention;

Fig. 2 is an enlarged pictorial view of the lower mounting of the heating element;

Fig. 3 is a bottom plan view, also enlarged, of the lower mounting;

Fig. 4 is an elevational view, partly in section, of the same lower mounting;

Figs. 5-8 are detail views showing the terminal construction employed in the heating element of Fig. 1;

Figs. 9-11 show a modification of the lower mounting shown in Figs. 2-4;

Figs. 12 and 13 show another construction therefor; and

Figs. 14-16 show still another construction. Except for the heating elements, the toaster

2

shown in Fig. 1 is substantially like that shown in U. S. Patent 2,012,788. It includes a plurality of individual oven chambers 10, each enclosed by a metal box having end walls 12 and side walls 14. The two heating elements 15, of which only one is shown, are disposed on opposite sides of this well-like oven space for toasting the two sides of a single piece of bread which may be supported on a carrier 18 and held away from contact with the heating elements by vertical guard wires 20. The bread-supporting rack 18 is moved up and down by mechanism not shown. It is moved down manually and it pops up under control of a suitable timer here shown as a clock 22, in a manner now well known. The toaster includes electric terminals 26, 27, 28 and 29, and also others (not shown) to which the heating elements may be connected.

The heating element 15 includes a glass tube 16 convoluted to substantially fill a square plane 20 and to have ends extending from the two upper corners. A convolute electric conductor 21 extends through this tube 16 and has metal terminal members 32 sealed in the ends of the tube 25 for attachment to the terminals 26 and 28 carried by the toaster frame. The pattern in which the tube 16 is bent comprises two half patterns, each composed of horizontal runs 17 connected together at their ends by U-bends, with a single long run 19 at the bottom for connecting the 30 two half patterns, as is shown in Fig. 1.

The convolute conductor 21 is in the form of a crimped ribbon, and the glass tube 16 is round so that the ribbon touches the tube only in a few spots. Thus as is indicated in the sectional view of Fig. 4, contact between the ribbon and glass can occur at most only at two points, such as 34, at the crest of each bend of the ribbon. Furthermore, the conductor lies loose in the tube so that actual contact occurs at only a few of 40 these points. This slight physical contact between the wire and the glass provides poor heat conduction to the glass and the transparency of the glass insures poor absorption of radiation. Consequently the cooling effect of the outside 45 air keeps the glass much cooler than the metal resistor. Preferably the element 15 is constructed as follows: A length of crimped ribbon is cut to the required value of electric resistance, then stretched out to the required length, provided with a seal-in lead (to be described presently), and inserted in a straight glass tube of the required length. The glass tube is then formed and the terminals 32 attached.

It is desirable that the convolute tube 16 be given support in addition to that at the terminals

32, but since glass reduces its electric resistance at high temperatures it is desirable also to provide a special insulating construction for such a support and thereby eliminate such electric-shock hazard as might result from letting the metal frame of the toaster touch an excessively hot portion of the glass tube.

A third support for the heating element includes a glass stub 36 that is fused to the bottom horizontal run 19 of the tube 16 and extends down therefrom. In the specific form here shown this stub consists of a piece of glass tube that sets over a pin 38 on a bracket 40 which is fastened to the wall 14 of the oven structure. The support tube 36 is simple, cheap, rugged and effective. Glass is a poor heat conductor compared to metals and therefore the metal bracket 40 cools at least that part of tube 36 that touches it. The air draft moves up through the oven space 10 and so carries heat away from the stub 36 and bracket 40 rather than toward them. Accordingly the stub tube 36 is far cooler than the resistor-containing tube 16 and so provides good electric insulation and presents no shock hazard to persons using the toaster.

Just above the bottom horizontal run 19 of the tube 16 is a bumper spring 42. As is shown best in Fig. 4, this spring is spaced slightly above the glass tube so that during the normal operation of the toaster it will not touch the glass. However, should the stub 36 be raised from its seat on bracket 40, as when the toaster is jolted or dropped, the tube stops against the bumper 42. The resilience of the glass tube 16 permits such movement of the bottom portion, and the bumper, by absorbing the shock, reduces the strain on other portions of the tube, particularly on the portions near the terminals 32. The bumper 42 is pivoted on a bracket 44 and has a slot 46 that may be engaged by a screw driver or the like for turning it into and out of the tube-retaining position in which it is shown in Figs. 1, 2 and 4. It is yieldingly held in that position by a spring washer 48 cooperating with cam surfaces 50 formed in the bumper 42 and bracket 44.

Figs. 5-8 show the construction of the terminals 32. The end of the heating-conductor ribbon 21 is doubled back on itself and spot-welded as at 50 to form a portion of double thickness as at 52 which will constitute a seal-in-lead. This lead may be conveniently formed before the ribbon is inserted in the glass tube 16. Then, the tube 16 having been formed, a short glass bushing 54 is slipped onto its end. A metal connector 56 is slipped into the other end of the bushing 54 and the end of the doubled lead 52 is threaded through the hole 58 in the connector and folded back. The terminal is completed by riveting a grommet 60 into hole 58 to clamp the lead 52, and by heating and pressing the two pieces of glass at 62 to fuse the bushing 54 and tube 16 together and to seal in the lead 52.

Figs. 9-11 show a modified construction of the lower mounting. Therein the spring bumper for the lower run 19 of the tube consists of a single spring strip 66 riveted to the bracket 40, and extending up alongside the stub 36 and over the tube 19 but spaced therefrom. Fig. 9 shows the position of the parts during normal use of the toaster. Fig. 10 shows how the spring 66 70 catches the tube with its hooked end 68 when a jolt unseats the stub 36. When a heating element is to be installed or removed, the spring may be bent to one side as in Fig. 11.

Figs. 12 and 13 show another construction for

the low-leakage support at the bottom of the heating element. There a depending glass stub 72 has a ring-like enlargement or flare 74 formed thereon. A bracket 76 mounted similarly to bracket 40 carries a spring clip 78 into which flare 74 may be pressed. The clip resiliently grips the tube 72 and resists displacement in any direction.

Figs. 14-16 show still another construction for the bottom support. There the bottom run 19 of tube 16 is provided with a ring-like enlargement or flare 82 which snaps into a spring clip 84 on a bracket 86 that is mounted similarly to bracket 40. Although the flare 82 will not provide as cool a glass-to-metal contact as will the other constructions it is cooler than the adjacent, unenlarged parts of the tube 19.

Of the several constructions for the lower support, that of Figs. 1-4 is the one I now prefer. 20 The glass is cool at its point of contact with the metal of bracket 40 to prevent objectionable leakage currents, and the spring bumper 12 positively prevents more than a slight lifting of the glass structure off bracket 40.

25 The structure of Figs. 9-11 similarly insures that the glass will be cool at the point of normal contact with the metal of the support. Although the bumper 66 permits somewhat more movement, it is cheaper and under certain conditions 30 can be moved aside more easily for the removal or insertion of the heating unit.

35 The structure of Figs. 12 and 13 provides a firm grip on the coolest part of the glass, and under certain conditions permits the removal and 40 insertion of the heating unit to be effected more easily than do the constructions of Figs. 2 and 9. The structure of Figs. 14-16 similarly provides a firm grip on the glass, and is cheaper than that of Figs. 12 and 13, but under similar operating conditions will not provide as cool a contact with the metal support.

45 I have found the heater construction of the present invention to be sufficiently resistant to mechanical shocks that it survives accidents that are likely to damage the case or other parts of the toaster. Further, I find that it has a low electric leakage through the glass to the frame, and is cheaper than prior constructions.

It will be apparent to those skilled in the art 50 that the invention is capable of numerous modifications and variations and accordingly the invention should be limited only by the scope of the appended claims.

I claim:

55 1. An improved electric heater for a toaster or the like consisting substantially of a glass tube convoluted in two zig-zag patterns each constituting substantially half of a plane, rectangular configuration, and each comprising a plurality of approximately parallel transverse runs connected only by U-bends near the longitudinal center line and an outer edge of the configuration, said patterns joining each other by a long transverse run along one edge of the configuration, means for supporting said convolute tube at only a few separated points, the tube being self supporting therebetween, and a heat-generating electric conductor extending through said tube.

60 2. An electric heater for a toaster or the like consisting substantially of a glass tube having two ends convoluted in two zig-zag patterns each constituting substantially half of a vertical, plane, rectangular configuration and comprising a plurality of approximately horizontal runs

connected by U-bends near the vertical center line and an outer edge of the configuration, each said pattern beginning at the upper outer corner and joining the other at the bottom center, an electric conductor extending through said tube, 5 and means near the ends of said tube and near said upper corners for supporting said tube.

3. The combination of claim 2 wherein said supporting means comprises terminals at the ends of said tube and at the said upper corners 10 of said configuration adapted to support said tube and facilitate its connection in an electric circuit.

4. The combination of claim 3 wherein there is included means for also supporting said tube near 15 the bottom of said configuration.

5. The combination of claim 3 wherein there is included a spring supporting clip for engaging said tube near the bottom of said configuration.

6. The combination of claim 2 wherein there is included a low-leakage support for the bottom run of said tube near the center thereof.

7. In an electric toaster or the like, in combination, a frame structure, a vertical, flexible, electric heating element consisting substantially of a glass tube convoluted in a planar pattern, a conductor in said tube, spaced terminals for said conductor at the upper edge of the pattern, and a glass projection extending down from a bottom run of said conductor-containing tube for providing a low-temperature support-engaging part, insulated terminal supports on said frame connected to said element terminals for supporting said element and connecting it in an electric circuit, a bottom support on said frame engaging 35 said projection and bearing up thereagainst for giving support to the lower part of said flexible heating element, and a bumper above said bottom run but spaced thereabove for preventing displacement of said element from said bottom support, but normally lying free of contact therewith.

8. The combination of claim 7 wherein said bumper comprising a horizontal spring strip and means for supporting it for swinging movement 40 about a vertical axis to swing out of said position.

9. The combination of claim 7 wherein said bumper comprises a deflectable hook-shaped spring.

10. In an electric toaster or the like, in combination, an electric heater consisting substantially of a glass tube having two ends convoluted in two zig-zag patterns each constituting substantially half of a vertical, plane, rectangular configuration and each including a plurality of approximately horizontal runs connected by U-bends near the vertical center line and an outer side 45 edge of the configuration, each said pattern be-

ginning at an upper corner of the configuration and joining the other by a long transverse run along the bottom edge of the configuration, an electric conductor extending through said tube, means near the ends of said tube and near said upper corners for supporting said tube, a short glass stub-tube fused to said transverse run at the bottom edge and extending down therefrom, and a support engaging the bottom end of said stub-tube.

11. The combination of claim 10 wherein there is included a resilient bumper above said transverse run of said tube and spaced therefrom, whereby to stop upward movement thereof but normally to remain out of direct contact therewith.

12. In an electric toaster or the like having therein an exposed conducting surface and an electric heating element having a high operating temperature, said heating element including a horizontally extending glass tube containing a heat-generating metallic element, the improvement which includes low-leakage means for supporting said tube intermediate its ends, said means consisting of an entirely metal-free supporting structure engaging the tube, said tube-engaging supporting structure consisting of a vertical hollow glass stub having its upper end fused to the side of the tube at an intermediate point, and further supporting means entirely spaced from the tube, said further supporting means consisting of a rigid metal member engaging the lower end of said glass stub and supporting the load of said glass stub and said horizontal tube.

JOHN R. GOMERSALL.
